(57) CLAIM

The ornamental design for an ornament for handbag, as shown and described.

DESCRIPTION

FIG. 1 is a first embodiment of a top perspective view of an ornament for handbag showing my new design;

FIG. 2 is a bottom perspective view thereof;

FIG. 3 is a top view thereof;

FIG. 4 is a bottom view thereof;

FIG. 5 is a side view thereof;

FIG. 6 is a front view thereof;

FIG. 7 is a rear view thereof; and

FIG. 8 is an environmental view thereof.

FIG. 9 is a top perspective view of a second embodiment of an ornament for handbag with solid lines showing my new design;

FIG. 10 is a bottom perspective view thereof;

FIG. 11 is a top view thereof;

FIG. 12 is a bottom view thereof;

FIG. 13 is a side view thereof;

FIG. 14 is a front view thereof;

FIG. 15 is a rear view thereof; and,

FIG. 16 is an environmental view thereof.

The portions of the handbag shown in broken lines form no part of the claimed design for an ornament for handbag.
